UNITED STATES PATENT OFFICE.

THOMAS F. MEYER, OF BRISTOL, WISCONSIN.

SILO-ROOF.

1,106,398.

Specification of Letters Patent. Patented Aug. 11, 1914.

Application filed April 16, 1913. Serial No. 761,538.

To all whom it may concern:

Be it known that I, THOMAS F. MEYER, a citizen of the United States, residing at Bristol, in the county of Kenosha and State of Wisconsin, have invented a new and useful Silo-Roof, of which the following is a specification.

This invention relates to an improved form of silo roof.

10 An object of the present invention is to provide a silo roof which may assume a conical form and act in the capacity of a roof or which may be assembled in the form of a hollow cylinder, in which shape it will 15 act as an extension for the side walls of a silo.

A further object is to provide a silo roof which may assume a cylindrical outline so that the ensilage may be positioned within 20 the silo and thereabove and allowed to settle after which the roof is folded to its conical shape and serves as a roof.

A further object is to provide a silo roof supporting structure which may be removed 25 from the silo when the latter is to be filled with ensilage.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made 35 within the scope of what is claimed, without departing from the spirit of the invention.

In the drawings accompanying this specification and forming a part thereof, the 40 preferable form of my invention is illustrated in which:

Figure 1 is a view in elevation illustrating my improved roof secured to a silo. Fig. 2 is a vertical cross sectional view thereof. 45 Fig. 3 represents the roof construction when the latter is assembled in the form of a cylinder and provides an extension for the silo walls. Fig. 4 is a horizontal cross sectional view taken on the line 4—4 of Fig. 3, the 50 said line being located at such point that the radius of curvature of the upper members is substantially equal to the radius of curvature of the roof forming members. Figs. 5 and 6 illustrate in perspective the 55 roof forming members. Figs. 7 and 8 represent a top and side view of a portion of

the roof holding structure. Fig. 9 is a fragmental view of the roof holding structure at a point near where it joins the silo walls. Fig. 10 illustrates the manner in 60 which a ring is mounted above the upper edge of the silo walls and secured thereto. Fig. 11 is a fragmental view of a modified form.

Referring to the drawings in which similar reference numerals designate corresponding parts throughout the several views, 1 represents the cylindrical side walls of a silo fitting over the upper edge of which is a clip member such as illustrated in Fig. 65 10 and which clip comprises the downwardly extending walls 2 and the crimped or bent portion 3 which is adapted to engage a metallic ring 4 which ring is held concentric of the silo walls a slight distance 70 above the upper extremity of the same.

The metallic ring 4 is adapted to support the silo roof thereon and provides means whereby the same may be secured to the edges of the silo walls. The roof supporting structure preferably made of iron comprises the central post 5 the lower extremity 80 of which rests against the horizontally extending members 6 the ends of which members are fragmentally illustrated in Fig. 9 85 of the drawings and comprise a bifurcated portion 7 adapted to engage the metallic ring 4. Pivotally secured to the cross members 6 of the roof supporting structure are the upright members 8 which are pivotally 90 secured at their upper extremities to a collar 9, which collar is formed integral with a sleeve 10 which is adapted to travel over the cylindrical post 5. The sleeve 10 is held in a raised position by a pin 11 or other 95 equivalent means. The construction of the sleeve 10 and the upright members 8 allows the entire roof supporting structure to be removed from the metallic ring 4 and to be 100 lifted from the top of the silo previous to the insertion of the ensilage therein.

The members which comprise the roof proper are formed in a plurality of sections such as illustrated in Figs. 5 and 6 of the drawings. The member as illustrated in 105 Fig. 5 of the drawings is one of a number of members 12 which are substantially 110 trapezoidal in outline and are curved so as to conform with the curvature of the silo walls. To the lower extremities of the members 12 are secured the members 13, one of which is shown in Fig. 5 with the central 115

portion thereof removed to illustrate the outstanding lugs 14 which are adapted to engage the metallic ring 4 and to secure the member 12 thereto. The outstanding portion 15 is adapted to contact with the side walls 1 of the silo and to form an air-tight joint therewith such as illustrated in Fig. 2 of the drawings. A flat metallic ring 16 is secured to the roof supporting members 8 and against which is adapted to contact the upper extremities of the trapezoidal members 12. The remaining portion of the roof is formed by means of the triangular members 17 which are provided with the downwardly extending portion 18 which is adapted to contact with the upper or smaller ends of the trapezoidal members 12 to form a seal joint therewith. The members 17 are adapted to contact and be supported by the metallic ring or band 16 and the upper ends of the said members 17 meet at the apex of the roof 19, at which point a metallic cone 20 is secured which holds the said members 17 in position and provides an air-tight or seal joint therewith. The members 12 and 17 are formed with grooved edges as illustrated and which provides that the said members will form a structure and will when assembled in position, form an air-tight roof.

It will be noted in this connection that other means may be utilized than the tongue and groove to effect a tight joint between the various members 12 and the member 17, as it is thought will be readily appreciated.

When it is desired to fill the silo to which my improved structure has been secured, the cap 20 is removed from the upper portion of the roof and the members 17 removed one by one, after which the members 12 are moved upwardly so as to be disengaged from the adjoining members and the members 12 are then rotated upon the ring 4, being mounted for such rotation by the outstanding lugs 14 illustrated in Fig. 5, until said members lie substantially parallel to the side walls of the silo with which they contact as illustrated in Fig. 3. The members 17 are then positioned between the members 12 with the vertex thereof pointing downward so as to form a circular wall as illustrated in Fig. 3 and which is in fact a continuation of the silo side walls, it being noted that the roof supporting structure which includes the post 5, the cross members 6 and the inclined members 8 may be removed from the silo previous to the positioning of the members 12 and 17 as per Fig. 3. The silo may now be filled and it is noted that a decided increase in the capacity thereof is obtained and that ensilage may be piled to the top of the extension formed by the members 12 and 17. The members 12 and 17 are maintained in this position until such time as the ensilage settles below the upper edge of the walls

1 at which time the roof supporting structure which may be folded during the non-use thereof, is positioned upon the metallic ring 1 and the band 16 positioned thereon and the members 12 and 17 then returned to their original positions to form a conical roof structure, which it is to be noted will form an air-tight juncture with the side walls of the silo.

In order that the roof formed by the members 12 and 17 may be held rigidly in place, a ring 21 is provided with a turn buckle 22 and the said ring is adapted to fit within suitable grooves 23 formed in the members 12 and 17 as illustrated. In order to provide that the juncture between the members 12 and 17 when in a roof forming position, will be air-tight, a band 24 is positioned thereon as more clearly shown in Fig. 2. In Fig. 1 of the drawings a dormer window 25 has been illustrated as being secured to one of the members 12 and it is to be understood that such changes may be made within the scope of the present invention.

When the silo wall is of considerable thickness, the clip member 2' as illustrated in Fig. 11 is used in which the metallic ring 4 is set adjacent the inner surface of the silo wall. Attention is also called to the fact that in this modified form the members 12 and 17 rest directly upon the clip member 2' so as to present a smooth and continuous surface with the silo wall. The members 13 and the outstanding lugs 14 are removed and a hoop-shaped band 15' inserted in place thereof. Mention is also made of the fact that the members 12 and 17 may be made of metal should it be so desired.

Having thus described the invention what I claim to be new and original with me is:

1. A silo roof comprising trapezoidal and triangular detachable members, adapted to form interchangeably a conical roof, and a cylindrical wall.

2. The combination with a silo of a roof supporting structure secured thereto, trapezoidal and triangular roof forming members adapted to interlock and form interchangeably a conical roof, and cylindrical silo wall extension.

3. The combination with a silo, of a metallic ring substantially equal in diameter to the diameter of the silo side wall and detachably supported a slight distance thereabove, a roof supporting structure comprising a central post, horizontal members secured to said post and engaging and supported by said ring, a sleeve journaled upon said post, and roof supporting members pivotally secured to said sleeve and to said horizontal members.

4. The combination with a silo, of a roof supporting structure secured thereto, roof forming members detachably secured to said

5 roof supporting structure, the said roof forming members provided with tongues and grooves adapted to interlock to form a sealed roof, said members adapted to inter-
5 engage to form a cylindrical wall extension for said silo, and means for holding said cylindrical wall extension rigidly in position.

5. The combination with a silo, of a me-
10 tallic ring mounted thereabove, trapezoidal members provided with outstanding lugs adapted to rotatably engage said ring, a roof supporting structure detachably secured to said ring and adapted to hold said
15 trapezoidal members in a roof forming po-
sition, triangular members supported by

20 said roof supporting structure abutting the upper extremities of said trapezoidal mem-
bers and meeting in an apex to thereby form a continuous conical roof, said trapezoidal members adapted to rotate upon said ring to a vertical position, said triangular mem-
bers adapted to interengage said trapezoidal members to thereby form a cylindrical wall extension of said silo.

25 In testimony that I claim the foregoing as my own, I have hereto affixed my signature in the presence of two witnesses.

THOMAS F. MEYER.
